The ornamental design for a hanging umbrella light, as shown and described.

DESCRIPTION

FIG. 1 is a top right rear perspective of a hanging umbrella light, showing the new design;

FIG. 2 is a rear view thereof;

FIG. 3 is a front view thereof;

FIG. 4 is a right view thereof;

FIG. 5 is a left view thereof;

FIG. 6 is a top view thereof;

FIG. 7 is a bottom view thereof; and,

FIG. 8 is a bottom left perspective thereof.

The broken lines in the drawings illustrate portions of the hanging umbrella light that form no part of the claimed design.
